CLIMATE CABINET

Ernst Homberger, Frankfort-on-the-Main, Germany, assignor to Franz Gutmann, Brooklyn, N. Y.

Application April 2, 1936, Serial No. 72,386
In Great Britain April 8, 1935

2 Claims. (Cl. 128—371).

This invention relates to a cabinet for the production of various climatic conditions in imitation as true as possible to nature, especially those conditions of the air and of the radiation having to be intentionally produced which usually exist for instance at certain altitudes and countries, as for instance in high mountains or at the seacoast, or in particularly dry, very sunny countries, and which just for this reason are used with satisfactory result for the treatment of certain diseases.

Every local climate consists of a number of different factors, such as for instance pressure, moisture, temperature and purity of the air and sometimes also of the actual degree of ionisation of the air and of the presence of radiations of different wave lengths from infra-red up to ultra-violet. The ozone percentage of the air may also be of importance.

It has already been proposed to artificially produce the one or the other or some of the factors of the different climates which have been recognized as favourable and to employ them for medical treatments, such as for instance air of lower pressure, dried air with ozone addition, further radiation with actinic waves and simultaneous admission of ozone. The invention is based on the knowledge that complete healing can be attained only if in a suitable cabinet all the required factors are simultaneously applied.

The cabinet according to the invention represents for the first time a practically useful device to expose a patient in the meaning of this new knowledge to the effects of pressure, moisture, temperature, purity, ionisation, percentage of ozone and oxygen of the air and of certain kinds of rays, simultaneously and independently the one of the other, these effects adapted to be regulated within certain limits. As it forms part of the new knowledge according to the invention that the favourable effects of the climatic factors can be further increased by treating the body of the patient at the same time directly with high frequency currents, provisions are made that by the arrangement according to the invention also the practical admission of such currents to the body of the patient is possible.

The special problem which is solved by the invention consists in that the above mentioned measures can be carried out securely in a restricted space in a simple manner and at the lowest possible expenses. The cabinet according to the invention comprises therefore in combination all the known means for the desired adjustment of pressure, moisture and temperature, for

the radiation with effective rays and for the high frequency treatment by means of a chair or the like constructed as electrode with direct metal contact on a large surface, one pole being connected to a high frequency generator, whereas the second pole of the source of current is earthed or connected to a metallic lining of the walls of the cabinet.

A suitable modification of the device is characterized in that the cabinet contains an apparatus for the admission of fresh, purified air, by means of which all the air contained in the cabinet is replaced by fresh air after the treatment of a patient and before the next patient enters the cabinet. The air purifier may be preferably arranged so that the air sucked into the same comes from the inside of the cabinet, the air in the cabinet carrying out a circulating movement in being purified, the pressure in the cabinet being not influenced thereby.

As the body of the patient is brought directly into intimate contact with a large surface metal electrode laid on a source of high frequency current, the energy of the source of high frequency current is not only employed for the charging or 20 arsonvalisation of the body but at the same time for the ionisation of the air which surrounds the body. The voltage may be selected so that really a perceptible ionisation occurs, the more so as in the most frequent cases of adjusting climate 30 at a high level, i.e. of low pressure, in the cabinet the ionisation is much easier than at normal pressure. As the electric proceedings which lead to the ionisation take place on the surface of the human body, the effect of the ionised air which surrounds the body becomes particularly effective.

An especially suitable form of construction of the arrangement is characterized thereby that the metal plate of the chair or the like coming into contact with the body of the patient is movable and coupled with a switch contact which, when the metal plate is depressed, switches in the high frequency generator or the high frequency circuit. If in this or in a similar manner the metal plate is put under voltage only by the weight of the body of the patient, the inconveniences are avoided which otherwise might result from the flashing over of little sparks shortly before the plate is touched. The employment of one and the same source of current 50 for the charging of the body and for the ionisation of the air, and the arrangement of a large contact surface of the electrode with the body are the reasons that a comparatively feeble source of current is sufficient for the whole 55

demand of high frequency, i. e. a small and cheap apparatus requiring little space which may even be accommodated under the chair.

Several embodiments of the invention are illustrated by way of example in the accompanying drawings in which:

Fig. 1 is an elevation of the cabinet, the front wall of the same with the door being omitted, this view being so to say a vertical section on line I—I of Fig. 2.

Fig. 2 is a section on line II—II of Fig. 1, i. e. a top plan view with omission of the ceiling.

Fig. 3 is a side elevation seen from the left side of Fig. 1, the fresh air producer being omitted, i. e. the connection being shown in section on line III—III of Figs. 1 and 2.

Fig. 3a shows in side elevation, partly in section a dry air filter which may in some cases be substituted for a purifier as shown in Fig. 3.

Fig. 4 shows in side elevation a modified construction of the chair mounted in the cabinet.

Fig. 5 shows on enlarged scale a high frequency producer with automatic switch.

Fig. 6 shows a modified construction of the switch.

The walls of the cabinet *a* have a lining *b* of sheet aluminium, which is suitable for different reasons, especially owing to the good reflexion of the rays especially the ultra-violet kinds of rays. A tightly closing door *c* adapted to be locked serves as entrance, whereas an observation window *d* allows of supervising the treatment. A chair *e* having a movable contact plate *e'* is placed in the centre of the cabinet *a*. The contact plate *e'* is coupled with a switch *e⁴*, which controls the connection *e''* of plate *e'* with the high frequency producer *e'''*. This high frequency producer is connected to the network by means of a connecting lead *e³*. The switch *e⁴* completes the high frequency circuit only if the weight of the body of the patient has depressed the plate *e'*. The surface of the plate coming into contact with the body is large enough to ensure electric charging of the body with little expense in electric energy and at the same time ionisation of the air which directly surrounds the body.

The suction conduit of an air pump or the like can be connected through a tube *f* fitted with a cock and leading into the cabinet. A quartz lamp *g* serves as source for the ultra-violet light, and a lamp *h* is provided for infra-red rays. An apparatus *i''* composed of several radially arranged lamps *i* possessing various properties may be further provided for the production of infra-red to ultra-violet rays.

The leads for the lamps are conducted airtightly at *g'*, *h'* and *i'* through the wall of the cabinet, same as the outside continuation of the inside lead *e³* for the high frequency transformer *e'''* accommodated under the chair *e*, said lead passing at *e²* through the wall of the cabinet. The outer ends of the leads terminate in plug contacts to be inserted into corresponding plug sockets *10* of the network. These plug connections are used instead of separate switch elements for the connected instruments. A conduit *k* for fresh air terminating in the cabinet has a branch *l* connected with the manometer *m*. A cock *n* permits of regulating the air admission. A liquid atomizer and air purifier *o* is mounted in the conduit *k*. If vacuum is produced in the cabinet *a* by means of the suction conduit *f*, fresh air in a quantity adapted to be regulated flows through the conduit *k* and the device *o*, the air being purified and if desired humidified. In the

atomizer *o*, liquid extracts and medicaments may be atomized instead of or besides of water. For certain purposes a dry air filter *o'* may be used instead of an atomizer *o* and consists substantially of a small chamber filled, similar to a scrubber, with many small rings or the like for enlarging the air paths and the surfaces in the filter. This is shown in Fig. 3a.

Fig. 4 shows that not only the contact plate *e'* of the chair is movable as in the form of construction Fig. 1, but the whole chair *e* which rests on springs *e⁵* so that it can descend under the action of the weight of the patient in guides *e⁶*.

A pin *e⁷* of electricity conducting material fixed under the seat of the chair actuates a switch *e⁴* of the high frequency producer *e'''* which is fixed on the floor. Only a resiliently movable and a stationary contact of switch *e⁴* are shown.

In the form of construction illustrated in Fig. 5 the plate *e¹⁰*, which may bear from below against the plate *e'* shown in Figs. 1, 2 and 4 respectively, or be fixed to the plate, is movable in vertical direction, a spring being inserted between the plate and the casing. A pin *e⁷* downwardly projecting from plate *e'* is adapted to 25 act upon the contacts *e⁴* of which only the lower stationary contact is connected with a secondary coil of the high frequency producer. Of this producer only the two coils are shown for clearness sake. The second pole of this secondary 30 coil is earthed by a lead *e⁸* or connected with the wall of the cabinet so that plate *e'* is unipolarly laid on the secondary coil as soon as the switch contacts are closed. A contact spring *e⁹* is intended to maintain the connection from 35 the secondary coil to the plate *e'*.

In Fig. 6 the switch *e⁴* is in the primary circuit of the high frequency producer *e'''*. The pin *e⁷* is insulated at the portion which touches the switch contacts.

Instruments arranged in the interior of the cabinet opposite the observation window *d* and designed for supervision of the different treatment factors by the doctor are not shown in the drawings.

If, in some cases, it is desired to produce an increase in pressure instead of a reduction of air pressure corresponding to the climate on high levels inside the cabinet, air under pressure is forced through the tube *f*. In this case 50 a branch of the conduit for air under pressure terminates in the liquid atomizer *o*, whereas the filter for purifying the air is preferably mounted in the pipe for air under pressure.

The tube *f* or a second similar tube *j* may also 55 be used for introducing pure oxygen into the cabinet.

After the naked patient has entered the cabinet and the door thereof has been tightly closed, the suction device (pump or the like) connected to 60 *f* is set in operation and the air pressure in the cabinet is reduced, that is to say, is brought to the desired pressure in accordance with the manometer. The reduction in air pressure is effected gradually so that the organism of the patient has time to adjust itself to this without injury. By reason of the reduction of the pressure (air dilution) occurring in the cabinet, slight quantities of fresh air are drawn in through the pipe *k*, this air being purified by passing through the 65 liquid atomizer *o* which may be replaced by a simple filter. The reduction in pressure in the cabinet produces a fine dispersion and atomizing of the liquid in *o* with which the fresh air drawn in is enriched. The quantities of fresh air which 70 75

are drawn in are controlled by means of the cock *n* or the like.

As soon as the patient sits on the chair *e* the high frequency device is switched on, that is to say, the body of the patient is charged with high frequency current and feeble ionisation of the air takes place. The ray treatment is then effected by switching on the lamps *g*, *h* and *i*. It will be understood that in the liquid atomizer *o* it is not only possible to disperse and atomize water, but also liquid extracts and medicaments and supply these to the interior of the cabinet. The instruments for observing the conditions inside the cabinet, in addition to the manometer, are not illustrated. They are provided in the cabinet directly behind the observation window *d* and can be observed through the latter.

The setting in operation, switching on and controlling of the various devices, is preferably effected from the outside which enables the attendant doctor to influence the conditions within in the cabinet and to vary these as required.

If instead of the conditions of the climate at a high level it is desired to produce those of a climate at a low level, for example a sea climate, fresh air is passed through the air purifier and liquid atomizer *o*, and provision made for the outflow of the consumed air. The liquid to be dispersed in this case is sea water or a dilute or medicament solution corresponding therewith.

In the event of a rather low or, generally speaking, a certain temperature having to be maintained or produced inside the cabinet, this may be done by way of a cooling plant combined with it in a manner as indicated in the drawings by way of example. A cooling coil *p* which may conveniently be the evaporator of the refrigerator or cooling machine is installed inside the cabinet *a* and connected by pipes *s* with a refrigerator or cooling machine *t* of any known type arranged outside the cabinet. Associated with the cooling coil *p* within the cabinet are a deflecting screen *q* and an electric fan *r* for ensuring a circulation of air. By controlling the operation of this installation the temperature inside the cabinet is at the same time controlled. The cooler may also be wholly arranged in the cabinet.

If needs be a device of some capacity for air conditioning, i. e. for washing and refreshing the air may be combined with the cabinet, as is also shown in the drawings. Such device comprises a column *u* partially filled with elements *w* presenting a large superficial area to water or other liquid sprayed by nozzles *x* and a fan *y* that blows fresh air from outside through the column *u* and a filter *z* into a tube *u'* and into the cabinet *a*. Within tube *u'* a valve *u''* is inserted 10 for sealing the cabinet at this point prior to altering the normal pressure of air in its interior.

Also the air purifying plant *u-z* may be mounted as a whole in the cabinet *a* if this should be desirable for special conditions and if the air 15 purifier is not destined for the admission of fresh air.

I claim:

1. A method for subjecting a human body to treatment by a desired condition of climatic air 20 and electric conditions substantially equivalent to natural conditions, such as in high mountains, dry sunny districts, or at the seashore, etc., which consists in producing an atmosphere of any one of said desired air conditions in an air-tight 25 chamber by conditioning the air therein from without said chamber, subjecting said confined conditioned air in the chamber to ionization by electric discharge rays, and subjecting the human body within said chamber to a high frequency 30 current therethrough by automatically closing a circuit therefor by a retiring movement of said human body within said chamber.

2. A therapeutic cabinet comprising an enclosed chamber having a metallic lining constructed to form a high frequency electrode, a seat mounted within the chamber and having a contact plate covering a substantial portion of the area thereof and constructed to form a high frequency electrode, switch means connected 35 with said seat and having operative connections with said electrode thereof to close a high frequency electric circuit to said seat electrode and the lining when a patient is sitting on the said electrode.

ERNST HOMBERGER.
